UNITED STATES PATENT OFFICE.

WILLIAM WALTER RUTTER, OF EDMONTON, ALBERTA, CANADA.

PNEUMATIC TOY.

1,242,870.

Specification of Letters Patent.

Patented Oct. 9, 1917.

Application filed September 27, 1916. Serial No. 122,509.

To all whom it may concern:

Be it known that I, WILLIAM WALTER RUTTER, a subject of the King of Great Britain, and residing at Edmonton, in the 5 Province of Alberta, Dominion of Canada, have invented certain new and useful Improvements in Pneumatic Toys, of which the following is a full description.

This invention relates to improvements 10 in toys of the pneumatic type and the objects of the invention are to provide a device for exercising and developing the lungs while at the same time affording a source of amusement to the user, and generally to 15 simplify the toy and render the several parts better adapted to perform the functions required of them, and it consists essentially of the improved construction particularly described and set forth in the following specification and accompanying drawings forming 20 part of the same.

In the drawings,

Figure 1 is a side elevation of the improved toy.

25 Fig. 2 is a fragmentary longitudinal section of the same.

Like characters of reference refer to like parts in all the figures.

Referring to the drawings, A represents 30 the improved toy comprising the tubular member 10 reduced at one end to form a mouth piece 11, the other end terminating in the wall 12.

The tubular member carries intermediate 35 of its length a cup 13 through the stem 14 of which a conduit 15 extends communicating with the interior of the tubular member, while located diametrically opposite the said conduit a depression 16 is formed 40 in the wall of the tubular member.

Operatively connected to the end 12 of the tubular member 10 is a supporting member 17 provided intermediate of its length with a curvilinear or semi-circular offset 45 portion 18 and terminating in the upper end in an overhanging hook member 19, the objects of which will be made clear hereafter.

The cup 13 is designed to support the ball 20 through which the wire 21 diametrically 50 extends, the lower end of the wire being designed to pass through the conduit 15 and engage with the depression 16, while the upper end terminates in an eyelet 22 adapted under certain circumstances to be engaged 55 to the hook 19.

The assembly of the toy will be readily understood from the foregoing description.

When the toy is in use the ball 20 is located in the cup 13 with the wire 21 passing through the conduits 15 and engaging the depression 16, and when the operator places the end 11 of the tubular member 10 in his mouth and blows through the same, the wind acting on the ball 20 displaces the same upwardly, and since the upper eyelet 22 is 60 slightly heavier than the lower end of the wire 21 the ball will tip and the said eyelet engage with the hook 19, assuming the position shown by the dotted lines in Fig. 1.

The height to which the ball 20 is displaced will depend on the wind pressure acting on the same, so that the user of the toy will have to regulate the said pressure and this will afford plenty of scope for amusement while at the same time developing the 75 lungs.

As many changes could be made in the above construction and many apparently widely different embodiments of my invention within the scope of the claims constructed without departing from the spirit or scope thereof, it is intended that all matter contained in the accompanying specification and drawings shall be interpreted as 80 illustrative and not in a limiting sense. 85

What I claim as my invention is:

1. A toy of the class described comprising a tubular member terminating in a closed end, a cup mounted on the tubular member and provided with a conduit communicating with the tubular member, a ball co-acting with the cup, a wire extending diametrically through and beyond the ball terminating at the upper end in an eyelet which upper projection more than balances the lower projection and a suspending member mounted on the tubular member wholly disposed laterally of the ball and designed to coact with the said eyelet. 90

2. A toy of the class described comprising a tubular member terminating in a closed end, and having a depression in the bottom, a cup located above the said depression, a ball coacting with the cup, a member extending diametrically through and beyond the ball and engaging on the lower end with the depression and terminating at the upper end in an eyelet which upper projection more than balances the lower projection and a suspending member mounted on 100 105 110

the tubular member designed to coact with the eyelet.

3. A toy of the class described comprising a tubular member terminating in a closed end, a suspending member operatively connected to the closed end and provided with an intermediate curvilinear portion and terminating at the upper end in an overhanging hook, a cup on the tubular member, a ball coacting with the cup, said hook being laterally disposed to the ball and a member

extending diametrically through and beyond the ball provided with an eyelet on the upper end designed to coact with the said hook which upper projection more than 15 balances the lower projection.

In witness whereof I have hereunto set my hand in the presence of two witnesses.

WILLIAM WALTER RUTTER.

Witnesses:

GEO. V. CARAHITSON,
C. M. BOTTON.
